UNITED STATES PATENT OFFICE

WADE H. REICHARD, OF ROCHESTER, NEW YORK, ASSIGNOR TO GENERAL RAILWAY SIGNAL COMPANY, OF ROCHESTER, NEW YORK

TRAIN-CONTROL SYSTEM

Application filed April 27, 1929. Serial No. 358,577.

This invention relates in general to an automatic train control system, and has more particular reference to an intermittent inductive alternating current type of system such as disclosed in the C. S. Bushnell application Ser. No. 171,821 filed March 1, 1927.

In train control systems it is desirable to have cooperating trackway and car-carried apparatus so arranged as to properly influence each other over a wide range of train speeds, and to be free from liability to short circuits and other defects. It is also desirable that should a short-circuit inadvertently occur, it should not result in a false clear indication.

With regard to the car-carried apparatus more particularly, it is desirable to have properly safeguarded acknowledging and reset means, whereby such means can not be improperly used to defeat the purposes of the system.

With the above and other objects in view, it is proposed, in accordance with this invention to provide cooperating car-carried and trackway receiver and inductor means capable of adjustment to provide for proper operation throughout all speeds of train movement ever encountered in practice, and arranged so that short-circuits will not result in false clear conditions being set up.

It is also proposed, according to this invention, to safeguard the acknowledging and reset means so that the acknowledging means can not be operated to defeat the usual purpose of acknowledging, and so that the reset means can not be operated under improper conditions and so that it must be restored to normal, after having been operated, before the train can proceed.

Further objects, purposes and characteristic features will appear as the description progresses, reference being had to the accompanying drawings, showing, solely by way of example, and in no manner in a limiting sense, one embodiment which the invention can assume. In the drawings:—

Fig. 1 is a schematic view of one embodiment of the invention.

Fig. 2 is a diagram illustrating the operation or portions of the system.

Referring now to the drawings, there is shown a stretch of single track constituted by track rails 1, separated in a usual manner into signalling blocks by insulating joints 2. At the entrance end to each block, travel being in the direction of the arrow, is positioned a wayside signal 3, which is controlled in any usual or desired manner, (not illustrated) to assume different positions so as to give proper indications in accordance with traffic conditions ahead. Assuming the wayside signals are arranged to give three indications, the signal 3 will be set at stop when its block is occupied, will be set at caution when its block is unoccupied but the block immediately beyond it is occupied, and will be set at proceed when its block and the block immediately beyond it are both unoccupied.

Positioned in the entrance end of each block is a wayside conductor *Ind*, constituted by two core portions 4 and 5, with their ends and center portions held together, as illustrated, and the intermediate portions bowed out. At each side of the bowed portions, is a laminated shelf or overhang 4¹ and 5¹, to give these parts of the core a double width for aiding in cooperation with the receiver to be described below. These core portions 4 and 5 are preferably of laminated material, with the laminations positioned in vertical planes, for example. Positioned on the cores at each end, are coils 6 and 7, connected up in series with each other through a tuning condenser 8 and a jumper 9, the circuit being adjusted to give a maximum clearing effect for the core portions adjacent the end coils, when passed over by a car-carried receiver, to be described below.

Positioned on the core portions 4 and 5, at an intermediate point, is a middle coil 10 which has connected across it a tuning condenser 11, the coil being connected in series with a second tuning condenser 12, a contact 13 of a line relay *LR*, and beyond the contact 13, an external inductive reactance or reflector 14.

As indicated, line relay *LR*, in conjunction with track relay *TR* and the track relay (not shown) for the block next in advance through a front point of which passes the

100

energizing circuit for LR, automatically controls the position of the contact finger 13, in accordance with traffic conditions, to either open or close the circuit including the middle 5 coil 10, condenser 12, and inductive reactance 14. This control is arranged, so that the circuit is broken under caution and stop conditions, and is made under proceed conditions.

The jumper 9 in the circuit including the 10 end coils 6 and 7 can, if desired, be removed so as to remove the shunt around a contact finger 13¹ (which is of course without function when so shunted) and thus place these coils under control of contact finger 13¹ of 15 relay TR to cause this circuit to be automatically controlled in the same manner as described above with regard to contact 13.

The purposes of the various controls just described with regard to the inductor will 20 appear as the description progresses.

Carried on the train and preferably on the locomotive or tender, represented diagrammatically by the wheels and axles 15, is carried apparatus including a receiver R 25 comprising a core 16, preferably of laminated material as in the case of the inductor, and in the general form of an H, and positioned as shown so as to pass over the inductor Ind, during travel of the train, to be 30 affected thereby in a manner to be described.

Carried on the receiver R are two primary windings P, connected in series with each other and with a tuning condenser 17, directly across the primary Pr of an auto- 25 transformer T energized from an alternating current generator 18, the condenser 17 tuning the primary circuit for the frequency employed, which is preferably higher than commercial frequencies may be, for example, 40 360 cycles per second.

Also carried on the receiver R, as shown, are two secondary coils S connected in series with each other and with a tuning condenser 19 and windings 21 carried on a laminated core 22 of a main relay MR, whereby 25 to energize the windings 21 and maintain the relay armature 23 in picked up position under normal conditions. The secondary circuit is tuned for the frequency employed, 50 when the armature 23 is picked up, but is detuned for this frequency, when the armature is in its released position.

For a more detailed description of the receiver R, reference is made to the application of W. H. Reichard, Serial No. 358,578 55 entitled, Train control car element and filed of even date herewith.

Controlled by the armature 23, is a valve 60 24 arranged, when in its shown position, to close communication between a pipe 25 leading, for example, to the large cylinder of a brake valve actuator, and an atmospheric vent port 26. The valve 24 is carried on a 65 stem 27 connected to a spring 28 fastened to

the armature 23, the spring 28 being retained by a rigid guard 29.

It is clear from the above, that on de-energization of the main relay MR, the tension spring 30, will rock armature 23 in a counter-clockwise direction, about its pivot 70 23¹ to open valve 24 and thus vent pipe 25, with a resultant automatic brake application.

Considering now the co-action between the receiver and the inductor, when entering a clear block the middle coil 10, as well as end coils 6 and 7, are in closed circuit condition, whereby the distribution of flux furnished by the primary windings P of the receiver R, and traversing the secondary windings S of the receiver, is not materially disturbed, since the various coils on the inductor operate to choke off passage of flux through the inductor, in very much the same manner as described, in somewhat more detail, in the P. X. Rice application, Serial No. 106,478 filed May 3, 1926. Under such conditions, the secondary windings S of the receiver have sufficient voltages induced therein to supply the main relay windings 90 21 with sufficient current to maintain armature 23 in attracted position and thus prevent a brake application.

On the train entering a caution or danger block, the inductor middle coil 10 is open 95 circuited at contact 13, condenser 11 connected across winding 10 being so arranged as to give a better stopping effect when contact finger 13 is open, than if the circuit of winding 10 were merely open and the condenser were not present to thereby remove the choking effect on all but the end portions of the inductor, so that the flux furnished by the primary coils of the receiver has alternative paths in opposite directions 100 through the receiver secondary windings, so as to reduce the current flow in the secondary circuit, normally energizing the main relay, to a low value, or to zero, or to actually reverse the direction of current flow, all 105 depending on the various constants involved, whereby to cause the main relay to release so as to open valve 24 and cause an automatic brake application. This operation is substantially the same as occurs in the Rice application, referred to above and also in the Rice Australian Patent 3,189 of 1926.

With the end windings 6 and 7 of the inductor connected up in a closed circuit, as illustrated, the two ends of the inductor are choked off, so that the receiver is practically unaffected when first passing onto the inductor, and upon leaving the inductor, while the effect of the central portion of the inductor, on the receiver, is determined by the middle coil 10, and the condition of its circuit automatically controlled by contact finger 13. If the end coils 6 and 7 were open circuited, the ends of the inductor would operate as permanent stop means, for 130

de-energizing the secondary windings on the receiver, and always cause a brake application, unless otherwise prevented.

At first sight it might be thought that the inductor, as described, might be made shorter by cutting off its ends, together with the end coils 6 and 7, without affecting the resulting control by the middle winding 10, but this is not the case.

If the inductor were made of the length shown in the drawing, but not furnished with the two end coils 6 and 7, the receiver, on first passing over the inductor, would receive a stop influence, and on leaving the inductor would receive a second stop influence. The first stop influence would continue up to the second stop influence, if the middle coil 10 were open circuited, but there would be a clearing influence, that is, relatively no change below normal in the receiver secondary current, in between, if the middle coil 10 be in a closed circuit. The two end coils, when short-circuited as shown, operate to prevent the initial and final stop influences referred to above, but cause the stop influence, which occurs when the middle coil is open circuited, to be of longer duration than if the entire inductor were made shorter by having its two ends which carry the end coils 6 and 7, entirely omitted. Thus the two end coils, short-circuited through the condenser 8, do very much more than in effect cutting off the ends of the inductor.

By this construction which results in the stopping effect, producible by the middle coil, being prolonged, a stopping effect can be obtained which is effective at higher speeds than would otherwise be obtainable. For example, with the present construction a stopping effect which is reliably effective for 80 miles per hour, might be so shortened in duration by omitting the end coils and the ends of the cores, as to be effective only for speeds up to 40 miles per hour.

The operation just described, is illustrated in Fig. 2, by the various curves there shown, which represent current induced in the secondary windings S of the car-carried receiver R, plotted against time.

The upper curve 31 represents the secondary current (current in 21) when the receiver is passing over an inductor at the entrance to a clear block, the current being diminished below normal only slightly, at most, when passing over a clearing inductor.

The curve 32 represents the receiver secondary current when the receiver passes over a stopping inductor, that is, an inductor with its middle coil 10 open circuited, with the inductor shortened by omitting the end coils 6 and 7 and the ends of the inductor core portions 4 and 5. This curve shows that the time during which the secondary current is below the drop-away current value (represented by line 35) for the main

relay MR, is relatively short as represented by the line 32¹.

With the inductor constructed as shown in the drawing, i. e., with the ends of the core choked by 6 and 7, the secondary receiver current, on the receiver passing over a stopping inductor, is represented by the curve 33, from which it is seen that, due to the short circuited end coils 6 and 7, and the longer inductor core, a considerably greater 75 duration, 33¹, of current value below drop-away value for the main relay, is realized.

Curve 34, in Fig. 2, represents the receiver secondary current, on the receiver passing over a stopping inductor in the case where 80 the end coils 6 and 7, as well as the middle coil 10, is open circuited. It is here seen that the duration, 34¹, of secondary current below drop-away value for the main relay, is still greater than in either of the two previous cases.

From the above description of Fig. 2, it is seen that a very considerable advantage is obtained by using the end coils 6 and 7, in their short circuited connection, over what 90 is obtained by shortening the entire inductor. In other words, the inductor as shown with a single middle coil controlled in accordance with traffic conditions ahead, gives a stopping effect which persists much longer 95 than would be the case without the end coils, although requiring automatic control of only the one winding, 10, on the inductor, i. e., the middle one.

It is obvious that the higher the speed of 100 the train, the shorter the time required for the receiver to traverse the various distances 32¹, 33¹ and 34¹, and hence the shorter the time during which the main relay is deprived of energizing current sufficient to 105 maintain it picked up, so that, with the described inductor, means are provided for adjusting it to satisfactorily operate at very high speeds.

Considering now the operation of the entire system, when a train equipped with the described system enters a clear block, the receiver R passes in inductive relation over the inductor Ind, but since the middle winding 10 of the inductor is included in a closed circuit through contact 13 to thus choke back any flux through the center portion of the inductor core, the receiver secondary current is not materially affected and the train can proceed past the signal at clear without 115 120 restriction.

It should be noted here, that receiver R, when over the inductor, parallels, and overlies only the shelf parts 4¹ and 5¹. Thus, with car side sway, movement of the receiver 125 sidewise, can at worst, increase the air gap between the inductor and the receiver, only at one of the two parallel legs of the receiver. This shows the advantage of the double width faces produced by parts 4-4¹, and 130

5—5¹, and insures proper control despite side sway.

Assume now that the train enters a caution or danger block, in which event the inductor is automatically controlled by relay 5 TR to have its middle coil 10 open circuited at the contact finger 13.

If the engineer be alert, and manifests his alertness by operating an acknowledging contact *Ack. G.*, the resulting de-energization of the secondary coils S of the receiver does not result in relay MR releasing its armature 23 and causing an automatic brake application. The acknowledging contactor is arranged, as shown, to operate normally open contact finger 51, 51¹, and a normally closed contact finger 52, the normally closed contact finger 52 being provided with a spring 53 and a retarding means 54, whereby contact 52 opens only some little time after operation of the contactor, as for instance, 15 seconds thereafter.

On operation of the acknowledging contactor *Ack. G.*, contact fingers 51, 51¹, and 52 complete a circuit for energizing relay MR regardless of the condition of the secondary receiver circuit, such acknowledging circuit including the secondary Sec. of the auto-transformer, normally closed contact finger 52, acknowledging contact finger 51¹ and back point, the two windings 21 of the main relay MR in series, acknowledging contact finger 51 and back point, to the other side of the transformer secondary.

The transformer T is so adjusted that this acknowledging circuit just referred to supplies enough current to the main relay to maintain it in attracted position, but insufficient current to pick it up after it is already in retracted position. Thus acknowledgment after release of relay MR is ineffective to restore the relay, while acknowledgment too great a time prior to reaching the stopping inductor, results in the acknowledging circuit being broken by opening of the normally closed contact finger 52 of the acknowledging contactor. In this manner the acknowledging device is protected against misuse.

Assume, however, that the engineer is not vigilant, and does not operate his acknowledging contactor, then, upon passing the stopping inductor, the secondary circuit of the receiver R is at least insufficiently energized to maintain the main relay armature 23 in its attracted position, with the result that such armature rocks in a counter-clockwise direction to open valve 24 to vent the large brake valve actuator cylinder and cause an automatic brake application.

In order that the train may proceed, the brakes must be released, and in order that the brakes be released, a reset contactor *Res. C.* must be operated. This reset contactor is positioned so as to be accessible only from

the ground, so that it cannot be operated until the train has come to a full stop. It might here be stated, of course, that speed control means might be used whereby the reset contactor becomes effective only at a very low speed, such as, for example, two miles per hour or the like, by use of a speed contact of any usual or desired design such for example as shown in the Rice application Ser. No. 729,823 filed August 2, 1924.

On the train coming to a stop, the engineer can alight and operate the reset contactor so as to close the normally open contact fingers 35 and 36, to thereby complete a reset circuit including; one side of the secondary of the auto-transformer, contact finger 35 and front point, the two windings 21, in series, of the main relay, reset contact finger 36 and front point, a reset tuning condenser 37 and back to the other side of the transformer secondary.

The tuning condenser 37 is adjusted to tune the reset circuit for the frequency employed, when the main relay has its armature 23 in released position, whereby sufficient current flows in the reset circuit to restore the main relay armature to picked up position and stop the venting of pipe 25 to atmosphere.

It should be noted that the acknowledging circuit referred to above includes no tuning condenser, and hence it is incapable of picking up the main relay after such relay has once released.

To protect the reset contactor from the misuse of, for example, tying it in operated position, a vent valve 38 is provided, having a stem 39 which is operated by the reset contactor when in operated position, to open pipe 40 which branches from pipe 25 to atmosphere, through a vent 41. In other words, in order to restore the main relay MR to attracted position, it is necessary to vent the pipe leading to the brake valve actuator. It is accordingly necessary, after having operated the reset contactor, to restore it to its normal position, (that shown), before it is possible to release the brakes to permit the train to proceed.

It will thus be seen that a system has been provided, including car-carried means having properly protected and safeguarded acknowledging and reset means, and also including cooperating inductively related car-carried and trackway receiver and inductor means, wherein the inductor means can be readily adjusted to cut in more or less controls to give stopping influences of varying durations, whereby to care for varying maximum speeds of train movement.

Referring to the inductor employed in this system, the series condenser 12, positioned to one side of the automatically controlled contact finger 13, and the series inductive reactance, or external reflector, positioned at

the other side of contact finger 13, together operate to tune the circuit including the middle inductor coil 10, so as to give the maximum possible clearing effect when the contact 13 is closed. The condenser 12 alone, or the inductive reactance 14 alone, gives only a very poor or imperfect clearing effect at best.

10 The wires 42 and 43, which run from the inductor, (which is of course enclosed in a housing together its coils and condensers), to the external reactor 14, are to some extent necessarily subject to accidental shorts. A short-circuit, however, between these two 15 wires, will include only the series condenser 12 and hence the inductor will be in stopping condition, due to the accidental short. Thus a decided advantage is obtained by placing part of the tuning means at each side of the 20 contact 13, in that accidental shorts can not result in false clear condition. In other words, the disposition of condenser 12 and reactor 14, eliminates the danger due to a short at the points at which shorts are most 25 likely to occur.

The above rather specific description of one form of the present invention is given solely by way of illustration, and is not intended, in any manner whatsoever, in a limiting sense. Obviously, the invention can assume many different physical forms, and is susceptible of numerous modifications, and all such forms and modifications are intended to be included in this application, as 30 come within the scope of the appended claims.

Having described my invention, I now claim:—

1. In a train control system, in combination, a relay normally energized by alternating current through a circuit tuned, when in attracted position, to the frequency of the alternating current employed, and controlled in accordance with traffic conditions ahead, an armature for the relay, a brake pipe, means controlled by the armature for venting the brake pipe to thereby cause an automatic brake application when the armature is released and to detune said tuned circuit, and reset means operable to complete a tuned energizing circuit for the relay and also to vent said brake pipe.

2. In a train control system, in combination, a relay normally energized by alternating current through a circuit tuned, when in attracted position, to the frequency of the alternating current employed, and controlled in accordance with traffic conditions ahead, an armature for the relay, a brake pipe, 55 means controlled by the armature for venting the brake pipe to thereby cause an automatic brake application when the armature is released and at the same time detune said tuned circuit, and acknowledging means operable to complete an energizing acknowl-

edging circuit for the relay regardless of traffic conditions, said acknowledging circuit being untuned for the frequency of current employed whereby acknowledgement is effective to prevent an automatic brake application only if performed before the relay releases, and reset means operable to complete a tuned energizing circuit for the relay and also to vent said brake pipe.

3. In train control systems, in combination, a wayside inductor having spaced legs, a car-carried receiver having spaced sides and positioned to pass over the inductor in inductive relation thereto, each of the sides being narrower by about one half than the 70 said legs in a direction transverse to the direction of travel, the outer edges of the legs being in vertical line with the outer edges of said spaced sides whereby to prevent car side-sway materially disturbing the inductive 75 positioning of the inductor and receiver.

4. In a train control system, in combination, a wayside inductor having spaced parallel legs, each leg having an inverted L 90 shaped cross section, a car-carried receiver having spaced sides and positioned to pass over the inductor in inductive relation thereto, in a direction transverse to the direction of travel, each of the sides being narrower 95 than the foot of the L of each said parallel leg, the outer edges of the sides being in vertical line with the outer edges of the said legs, whereby to prevent car side sway materially disturbing the inductive positioning of 100 the inductor and receiver.

5. In a train control system, in combination, a wayside inductor having spaced parallel legs, each leg having an inverted L 105 shaped cross section, with the feet of the L's of the parallel legs directed away from each other, a car-carried receiver having spaced sides and positioned to pass over the inductor in inductive relation thereto in a direction transverse to the direction of travel, each of the sides being narrower than the foot of the L of each said parallel leg, the outer edges of the sides being in vertical line with the outer edges of the said legs, whereby to prevent car side sway materially 115 disturbing the inductive positioning of the inductor and receiver.

In testimony whereof I affix my signature.
WADE H. REICHARD.
